UNITED STATES PATENT OFFICE

WILHELM LOUIS MORTZ, OF WANDSBEK, NEAR HAMBURG, GERMANY

LOADING PLANT

Application filed June 7, 1927, Serial No. 197,120, and in Germany November 25, 1926.

This invention relates to a loading-plant especially designed for building-stones of any kind, such as lime stones or sand stones, bricks, clinkers and the like. The apparatus is designed to pull the material from the hardening-boilers, or kilns on platform-wagons onto a loading-bridge and thence upon the conveying-wagon.

According to the invention this is made possible by pulling the platform-wagons, which are in the hardening-boilers, kilns or the like loaded with bricks or stones, by means of a pull-rope upon a loading-bridge mounted in a ditch on rails, this loading-bridge being then pulled out by the same rope from the ditch and rolled to a stopping-device so that, by the same rope, the loading-material can be pulled from the bridge onto the conveying-wagon which, standing in front of the engine-house in which the winch for the pull-rope is mounted, is held by means of oscillatable hook-shaped arms so that it cannot shift in the longitudinal or transverse direction with regard to the track.

An embodiment of the invention is shown, by way of example, in the accompanying drawings, in

Fig. 1 in side elevation partly in section and in

Fig. 2 in top plan view partly in section.

Figs. 1^a and 2^a are continuations of Fig. 1 and Fig. 2 respectively.

In front of the hardening-boiler, brick-kiln or the like for the stones or bricks to be loaded a ditch *a* is arranged in which a loading-bridge *c* is standing on a track *b*. The bricks *e* or stones piled in the hardening-boilers and the like upon platform-wagons *d* are pulled upon the loading-bridge *c* by means of a pull-rope *f* through the intermediary of a capstan *g*.

On each loading-bridge two platform-wagons *d* can stand.

The pull-rope *f* is operated from an engine (motor) *h* by means of a gear-wheel-mechanism *i* and rope-pulleys *k* accommodated in an engine-house *l* at the end of the track *b*. The track *b* does not extend close to the engine-house but leaves, in front of the same,

sufficient free space for a conveying-wagon *m*. A rack *n* at the end of the track forms a stop for the loading-bridge as it can securely hold a supporting arm *o* of said bridge.

On the bridge *c* a trap *p* is arranged which is balanced by a counter-weight *q* with pull-rope *r*.

On the engine-house *l* arms *s* having hooks at the front end are oscillatably mounted which are controlled by pull ropes *s* and counter-weights *q*.

The operation is as follows:

After the platform-wagons *d* loaded with stones or bricks have been pulled from the hardening-boilers, kilns or the like upon the loading-bridge *c* by means of the pull-rope *f* with the aid of the capstan *g*, the loading-bridge *c* is pulled by means of this pull-rope *f* from the ditch *a* on the track *b* up to the stop or rack *n* which stops the loading-bridge through the intermediary of the arm *o*. When trap *p* has been lowered onto the conveying-wagon *m*, which is blocked in its position by the lowered hook-shaped arm *s* against accidental shifting in longitudinal or transverse direction, the stones or bricks can be pulled by means of the pull-rope *f* onto the conveying-wagon *m*.

The advantage of this improved loading-plant in comparison with the commonly used loading-plants or apparatus is, that only one single winch is sufficient for pulling the platform-wagons from the kiln, for conveying the loading-bridge and for transferring the bricks or stones from the loading-bridge onto the conveying-wagon. Up to the present two separate small engine-houses, each with its driving engine consisting of an electric common oil or benzine-motor, were required so that a rational and economical working is impossible. The double engine-houses, double engines and accessories consume double power and demand the double attendance.

A serious inconvenience of the commonly used loading-system is that much time is lost during the transferring of the charge by troublesome lowering and elevating. By the high stress to which the engine and mechanism are submitted, the elements which ex-

cute a sliding, rubbing or rotating action, are excessively worn the more as sand gets between the elements so that the plant becomes frequently unfit for use for a longer or shorter time.

5 In addition to the enormous cost for repair a considerable loss is caused by the impossibility to use the plant. All these inconveniences are obviated by the new system, the 10 working process being considerably shortened, the cost of one engine-house and engine, the power to operate the latter as well as the wages of the engineer being saved. No slow elevating, lowering and pushing over of the 15 material is necessary which operations consume much energy.

Repairs are almost excluded and can scarcely happen in the plant according to the invention so that no interruption of work will occur. The initial expenses are less than half 20 of the expenses for the commonly used loading-plants, the efficiency being much greater.

I claim:—

A loading-plant for stones hardened in 25 hardening-boilers, comprising in combination platform-wagons for the material in the hardening-boilers, a ditch in front of the hardening-boiler, an engine-house at some distance from said hardening-boiler, a track 30 in said ditch and extending to a short distance from said engine-house, a loading bridge in said ditch on said track, a trap on the front end of said loading bridge, a conveying wagon between said engine-house and 35 the track end, a capstan on said track, a winch in said engine-house, an engine for driving said winch, a pull rope from said engine-house for pulling said platform-wagons with the material onto said loading- 40 bridge, and for pulling said loading bridge over said track to said conveying wagon, and the material from said loading bridge over said trap onto said conveying wagon, an arm downwardly inclined and fixed on the axle of 45 the front wheels of said loading-bridge, a stop consisting of a rack at the end of said track designed to securely hold said inclined arm, and arms having hooks, oscillatably mounted on the outer wall of said engine- 50 house and designed to securely hold said conveying wagon so that it cannot shift in any direction with regard to said track.

In testimony whereof I affix my signature.

WILHELM LOUIS MÖRTZ.
